RECOIL-REDUCING AND SHOT-PATTERN-CONTROLLING DEVICE FOR SHOTGUNS

Darwin Tucker Ennis, Las Vegas, Nev.

Application November 6, 1947, Serial No. 784,386

3 Claims. (Cl. 42—79)

1

This invention relates to a combination recoil-reducing and shot pattern controlling device for shotguns, and contemplates an efficient device of this kind adapted for attachment to a shotgun barrel, which device will materially reduce recoil and will enable ready control of pattern.

An object of the present invention is to provide a device of the above kind embodying a casing defining an expansion chamber and provided at its outer end with gas discharge openings disposed substantially parallel with the axis of said chamber to facilitate the escape of gas from the latter instead of deflecting the gas laterally through side openings at a right angle to such axis.

Another object is to provide a device of the above kind including a re-grouping member at the outer end of the expansion chamber casing for re-grouping the shot after passing through and spreading laterally in said casing, and a fixed choke or pattern-control muzzle removably coupled to the outer end of said re-grouping member so that any degree of shot performance may be secured by readily substituting one choke or pattern-control muzzle for another whose bore has a different recompression taper.

The re-grouping member has an external annular flange at its inner end which is preferably integrally joined at its outer edge to the casing and which is provided with a circular series of the gas-escape openings.

The re-grouping member has a rearwardly enlarged rear mouth portion whose sloping surface defines a compression chamber and merges with a substantially cylindrical front bore or throat conforming to the largest desired shot pattern.

The exact nature of the present invention, as well as other objects and features thereof, will become apparent from the following description when considered in connection with the accompanying drawing, in which:

Figure 1 is a side elevational view showing a recoil-reducing and shot pattern-controlling device constructed in accordance with the present invention and applied to the barrel of a shotgun;

Figure 2 is a view similar to Figure 1 with the major portion of the present device in central longitudinal section;

Figure 3 is a transverse section on line 3—3 of Figure 2;

Figure 4 is a transverse section taken on line 4—4 of Figure 2;

Figure 5 is a side elevational view of the removable choke or pattern-control muzzle; and

Figure 6 is an end elevation looking toward the right of Figure 5.

Referring in detail to the drawing, 5 indicates a shotgun barrel having a collar 6 suitably secured on the forward end thereof. The collar 6 has an externally reduced and threaded for-

2

ward end portion 7 onto which is screwed the rear end of a cylindrical casing 8 that defines an expansion chamber 9 therein.

A shot re-grouping member 10 is provided at the outer or front end of the casing 8, for re-grouping the shot after passing through and spreading laterally in the chamber 9. This re-grouping member has a rearwardly enlarged rear mouth portion 11 whose sloping surface defines a compression chamber and merges with a substantially cylindrical front bore or throat 12 conforming to the largest desired shot pattern. Also, the re-grouping member 10 has an external annular flange 13 at its inner end which is preferably integrally joined at its outer edge to the casing as shown, and which is provided with a circular series of gas-escape openings 14 disposed substantially parallel with the axis of chamber 9 to facilitate the escape of gas from the latter, instead of deflecting the gas laterally through side openings at a right angle to such axis.

A fixed choke or pattern-control muzzle 15 is removably coupled to the outer end of the re-grouping member 10, so that any degree of shot performance may be secured by readily substituting one choke or pattern-control muzzle for another whose bore has a different recompression taper. The tapered bore of the choke or muzzle 15 is indicated at 16.

Means is provided to facilitate quick attachment of the choke or muzzle 15 to or removal of the same from the re-grouping member 10, and to rigidly lock said choke or muzzle in place so that a gas-tight joint between said member and said muzzle is had. The outer surface of the re-grouping member 10 is screw-threaded to adjustably receive an internally threaded tubular coupling member 17. The front end of this coupling member has a pair of longitudinal slots 18 formed in its inner surface, which slots terminate in an annular groove or channel 19. Near its inner or rear end, the choke or muzzle 15 has an external annular flange 20 serving as a stop against the outer end of the coupling member 17.

At its inner or rear end, the choke or muzzle 15 is provided with a pair of peripheral, outwardly projecting lugs 21 which are the counterpart, in size and spacing, of the longitudinal slots 18 in the coupling member 17 and which are adapted to fit in the annular recess 19 thereof. This arrangement constitutes, in effect, a pair of bayonet joints, whereby the choke or muzzle 15 may be firmly locked on the outer end of the re-grouping member 10, the joint between the adjacent ends 55 of the parts 10 and 15 being made gas-tight by machining said ends and through the medium of screwing the coupling member 17 onto the re-grouping member 10 as far as possible. In order to insure the proper positioning of the choke or muzzle 15 relative to coupling member 17, a pin

22 is extended between and anchored in an end of each lug 21 and the flange 20, in position to constitute a stop for the lug engageable with a side wall of the adjacent slot 18 as shown in Figure 4, thereby preventing excessive turning of the choke or muzzle 15 relative to the coupling member 17. It will be seen that, upon slight loosening or unscrewing of the coupling member 17, the choke or muzzle 15 is released so that it may be freely turned to register the lugs 21 with the slots 18 and to thereby permit ready removal of the choke or muzzle. Conversely, the lugs 21 may be readily registered with and entered in the slots 18, whereupon the choke or muzzle 15 may be turned to the position of Figure 4 to connect the choke or muzzle to the coupling member. The coupling member may then be readily screwed further onto re-grouping member 16 and tightened so as to rigidly mount said choke or muzzle in place and to secure a gas-tight joint between the parts 10 and 15.

It will be noted that the inner end of the coupling member 17 is tapered rearwardly as at 23 so as to deflect the gas forwardly and laterally as it emerges from the gas-escape openings 14. This provides a slight change in course of the discharged gases and offers little resistance to discharge of the same.

From the foregoing description, it is believed that the construction, operation and advantages of the present invention will be readily understood and appreciated by those skilled in the art. Modifications and changes in details of construction are contemplated, such as fairly fall within the spirit and scope of the invention as claimed.

Having described the invention, what is claimed as new is:

1. In a recoil-reducing and shot pattern-controlling device for shotguns, a cylindrical casing adapted at its inner end for attachment to a shotgun barrel and defining a cylindrical expansion chamber therein, a cylindrical shot re-grouping member carried by the outer end of the casing and having a rearwardly enlarged rear mouth portion for re-grouping a charge of shot after passing through and spreading laterally in said expansion chamber, said shot re-grouping member having a threaded outer cylindrical surface for connection of a choke therewith, and an annular flange integrally connecting the inner end of the shot re-grouping member with the outer end of the casing, said flange having an annular series of small and closely related straight cylindrical gas-escape openings therethrough disposed parallel

with the axis of said chamber, said openings being arranged in a circle outwardly of and concentric with the cylindrical outer surface of said shot-re-grouping member.

5 2. In a recoil-reducing and shot pattern-controlling device for shotguns, a shot re-grouping member, a fixed choke butted at butted end against an end of the shot re-grouping member, said choke being formed near said butted end with an external annular flange and at said one end in spaced relation to said flange with a plurality of peripheral outwardly projecting lugs, and a coupling member provided at one end with a plurality of slots in its inner surface terminating in an annular groove and being the counterpart of said lugs, said lugs and said slots and groove providing a plurality of bayonet joints whereby the choke may be quickly mounted on and removed from the outer end of the shot re-grouping member, said coupling member being 10 15 20 adjustably fitted on said shot re-grouping member to tightly draw the choke against said shot re-grouping member.

3. In a recoil-reducing and shot pattern-controlling device for shotguns, a shot re-grouping member, a fixed choke butted at one end against an end of the shot re-grouping member, a coupling member adjustably threaded on said shot 25 30 35 re-grouping member, and coacting elements on the adjacent ends of the choke and the coupling member providing a quick detachable connection therebetween, said coupling member being adjustable to draw the choke tightly against said shot re-grouping member.
